UNITED STATES PATENT OFFICE.

GEORGE P. ABORN, OF WABAN, MASSACHUSETTS, ASSIGNOR TO WORTHINGTON PUMP AND MACHINERY CORPORATION, OF NEW YORK, N. Y., A CORPORATION OF VIRGINIA.

ENGINE VALVE.

Application filed May 29, 1926. Serial No. 112,462.

This invention relates to steam engines equipped with fluid actuated valves and more especially to internal valve gear for direct acting steam pumping engines in which a pressure actuated main valve governing the distribution of steam to the opposite sides of the working piston is controlled by a pressure actuated auxiliary valve.

Among the objects of the invention are the provision of certain improvements in the construction and mode of operation of such valve gear, insuring the efficiency and reliability thereof and providing a simple, compact and durable inside steam valve gear.

In the accompanying drawings forming a part of this specification there is shown by way of illustration a preferred embodiment of the invention and this construction will now be described in detail and the features forming the invention then specifically pointed out in the claims.

In the drawings,—

Figure 1 is a view of the device in longitudinal section with some of the parts broken away;

Figure 2 is a transverse sectional view thereof on the line 2—2 of Figure 1;

Figure 3 is a top plan view of the main valve seat;

Figure 4 is a section on the line 4—4 of Figure 3;

Figure 5 is a sectional view on the line 5—5 of Figure 3;

Figure 6 is a diagrammatic view;

Figure 7 is an enlarged top plan view of the main valve and its seat;

Figure 8 is a top plan view of the auxiliary valve seat; and

Figure 9 is a top plan view of the auxiliary valve.

Referring to the drawings, A is the engine cylinder within which reciprocates the main piston 10. The cylinder A is provided with the usual seat 11 for the valve chest B and a main valve seat 12 having steam ports and passages 13, 14, for the delivery of steam to and from the opposite ends of the cylinder A and an exhaust port and passage 15, these ports being controlled by a main valve 16 which may be of the common D-type shown. Steam is supplied to the valve chest B through passage 17 in the steam chest seat 11 and the exhaust from passage 15 is discharged through exhaust outlet 18, as

usual, and as shown, for instance, in my prior Patent No. 1,102,181.

The main valve 16 is moved across its seat by a main valve plunger 19 providing two pistons 20, 21, operating respectively within main valve plunger cylinders 22, 23, formed within the valve chest B. Steam is delivered to and from the main valve plunger cylinders 22, 23, through respectively passages 1 and 2 running through the main valve plunger 19 and terminating in an auxiliary valve seat 24 provided with an exhaust port 3, these ports being under the control of a suitable auxiliary valve 4. The main valve 16 has a cylindrical projection 25 fitting within a recess 26 in the central part of the auxiliary plunger 19 so that the valve 16 is moved by the plunger 19 while free therefrom for movement toward and from its seat 12, and a passage 27 extending through the projection 25 to connect the exhaust port 3 of the auxiliary valve seat 24 with the main valve cavity for exhaust through exhaust port and passage 15.

The auxiliary valve 4 is moved across its seat by an auxiliary plunger 28, providing two pistons 29, 30, for which suitable cylinders 31, 32, are provided in the valve chest B. Steam is delivered to the cylinders 31, 32, respectively through passages 5, 6, opening into ports on opposite sides of the main valve seat 12 and steam is exhausted therefrom through passages 7, 8, opening into ports on the same sides of the main valve seat 12 as, respectively, ports 5, 6. The main valve seat 12 is provided with steam supply ports and passages 9, 9', between, respectively, the ports 5, 7, and the ports 6, 8, which connect with the opposite ends of the engine cylinder A. Grooves a, b, in the opposite edges of the main valve 16 are adapted to connect, respectively, the ports 9 to 5 and 9' to 6 for supply of steam to the proper auxiliary cylinder and exhaust ports 7, 8, are connected at the proper time to main exhaust port 15 by, respectively, slotted grooves c, d.

The auxiliary valve plunger 28 may be locked by steam pressure applied thereon at the end of its movement and for this purpose it may be provided with suitable piston projections 33, 34, operating within cylinders 35, 36, formed in the valve chest B. Steam is supplied to and exhausted from the cylinders

35, 36, through, respectively, passages 37, 38, which are preferably controlled by the main valve 16 and may open, respectively, into main valve seat passages 13, 14, as shown.

5 The device operates as follows:

With the parts in the position shown in Figures 1 and 6, steam is supplied from the valve chest B through port and passage 13 to the left hand end of the main cylinder A 10 for movement of the main piston 10 toward the right, the main valve 16 at this time connecting passage 14 with exhaust passage 15 for exhaust of steam from the opposite side of the main piston, and connecting ports 9' 15 and 6 through groove b for delivery of steam to auxiliary plunger cylinder 32 at the proper time, and connecting port 7 to exhaust port 15 through slotted groove c for exhaust of steam from auxiliary plunger cylinder 31, the main valve being held in this 20 position by steam passing through the uncovered end of port 1 to main valve plunger cylinder 22. As the main piston 10 continues its movement, it uncovers port and passage 9' for delivery of steam through groove b and port and passage 6 to auxiliary cylinder 32 for movement of auxiliary plunger 28 and auxiliary valve 4 by piston 30. During this movement of the auxiliary 25 plunger 28, auxiliary plunger cylinder 31 is connected through port and passage 7 and slotted groove c to the main exhaust port 15 for exhaust of steam therefrom and the early portion only of its movement is opposed by steam pressure within locking cylinder 35 on locking plunger 33. This pressure, however, 30 is removed when the auxiliary valve 4 has moved sufficiently to uncover port and passage 2 for the delivery of steam to main valve plunger cylinder 28, and connect port 1 to exhaust port 3 for the exhaust of steam from main valve plunger cylinder 22, thus producing movement of main valve plunger to the left. This movement of the main 35 valve plunger 19 causes the main valve to open port and passage 14 for the supply of steam to the right hand end of the engine cylinder A, simultaneously connecting the opposite end to exhaust through port 13 and exhaust port 15. Immediately the ports 13 and 14 are connected in this manner steam is exhausted from locking plunger cylinder 35 through passage 37 and supplied to locking plunger 34 and cylinder 36 through passage 38.

The opposite stroke of the piston 10 is accomplished by a reversal of the movements above described.

The movements of the auxiliary plunger 40 28 may be cushioned by locating the exhaust passages for the auxiliary cylinders 31, 32, as shown, so that they are overrun by the auxiliary pistons 29, 30, and the auxiliary plunger 28 and main valve plunger 19 preferably move transversely to each other so

that their combined movements cause auxiliary ports 1 or 2 to be covered by the edge of the auxiliary valve 4 near the end of the movement of the main valve plunger 19 for cushioning thereof.

The main valve 16 and auxiliary valve 4 may be held to their seats in any suitable manner but are preferably held yieldingly to their seats by, respectively, springs 39 and 40, substantially as shown.

It will be understood that the invention is not to be limited to the specific construction or arrangement of the parts illustrated but that these may be modified within the invention.

What I claim is:

1. In a steam engine valve gear, the combination with a steam cylinder having steam and exhaust ports, of a main valve controlling said ports, a plunger moving the main valve, an auxiliary valve mounted on the main valve plunger and moving transversely thereto for controlling the supply of steam to and from the opposite ends of said plunger, and auxiliary valve plunger moving the auxiliary valve, means controlled by the main valve for moving the auxiliary plunger by steam from the steam cylinder, and means for applying steam pressure on the auxiliary plunger for locking it in position at the end of its movement.

2. In a steam engine valve gear, the combination with a cylinder having steam and exhaust ports, of a main valve controlling said ports, a plunger for moving the main valve, an auxiliary valve for controlling the supply of steam to and from the opposite ends of the main valve plunger and mounted on the main valve plunger and moving transversely thereto, an auxiliary plunger for moving the auxiliary valve, ports and passages controlled by the main valve for the delivery of steam to and from the opposite ends of the auxiliary plunger, locking plungers carried by the auxiliary valve plunger, and means for applying live steam on the locking plungers.

3. In a steam engine valve gear, the combination with a cylinder having steam and exhaust ports, of a main valve controlling said ports, a plunger for moving the main valve, an auxiliary valve for controlling the supply of steam to and from the opposite ends of the main valve plunger and mounted on the main valve plunger and moving transversely thereto, an auxiliary plunger for moving the auxiliary valve, ports and passages controlled by the main valve for the delivery of steam to and from the opposite ends of the auxiliary plunger, locking plungers carried by the auxiliary valve plunger, and means controlled by the main valve for applying live steam on the locking plungers.

4. In a steam engine valve gear, the com-

5 combination with a cylinder having steam and exhaust ports, of a main valve controlling said ports, a plunger for moving the main valve, an auxiliary valve for controlling the supply of steam to and from the opposite ends of the main valve plunger and mounted on the main valve plunger and moving transversely thereto, an auxiliary plunger for moving the auxiliary valve, ports and 10 passages controlled by the main valve for the delivery of steam to and from the opposite ends of the auxiliary plunger, means for cushioning the movements of the main valve plunger, means for cushioning the 15 movements of the auxiliary valve plunger, locking plungers carried by the auxiliary valve plunger, and means for applying live steam on the locking plungers.

5. In a steam engine valve gear, the combination with a cylinder having steam and exhaust ports, of a main valve controlling said ports, a plunger for moving the main valve, an auxiliary valve for controlling the supply of steam to and from the opposite 20 ends of the main valve plunger and mounted on the main valve plunger and moving transversely thereto, an auxiliary plunger for moving the auxiliary valve, ports and passages controlled by the main valve for the delivery of steam to and from the opposite ends of the auxiliary plunger, means for cushioning the movements of the main valve plunger, means for cushioning the 25 movements of the auxiliary valve plunger, locking plungers carried by the auxiliary valve plunger, and means for applying live steam on the locking plungers.

30

6. In a steam engine valve gear, the combination with a cylinder having steam and exhaust ports, of a fluid actuated main valve controlling said ports, an auxiliary valve controlling the movement of the main valve, an auxiliary plunger for moving the auxiliary valve, a port and passage in the main valve seat for delivery of steam to each end of the auxiliary plunger, a steam supply port and passage in the main valve seat for each of said ports and passages opening into opposite ends of the cylinder, a groove in the main valve for connecting each of said ports and passages with its steam supply port and passage, an exhaust port and passage in the main valve seat for each end of the auxiliary plunger, a slotted groove in the main valve 35 for connecting each of said auxiliary cylinder exhaust ports and passages with the cylinder exhaust port, locking plungers forming extensions on the auxiliary plunger, and ports and passages controlled by the main valve for applying locking steam on the locking plungers.

6. In a steam engine valve gear, the combination with a cylinder having steam and exhaust ports, of a fluid actuated main valve controlling said ports, an auxiliary valve controlling the movement of the main valve, an auxiliary plunger for moving the auxiliary valve, a port and passage in the main valve seat for delivery of steam to each end of the auxiliary plunger, a steam supply port and passage in the main valve seat for each of said ports and passages opening into opposite ends of the cylinder, a groove in the main valve for connecting each of said ports and passages with its steam supply port and passage, an exhaust port and passage in the main valve seat for each end of the auxiliary plunger, a slotted groove in the main valve 40 for connecting each of said auxiliary cylinder exhaust ports and passages with the cylinder exhaust port, locking plungers forming extensions on the auxiliary plunger, and ports and passages controlled by the main valve for applying locking steam on the locking plungers.

In testimony whereof, I have hereunto set my hand.

GEORGE P. ABORN.
